UNITED STATES PATENT OFFICE.

ALEXIS VERNAZ, OF YVERDON, SWITZERLAND.

FILE.

No. 807,143.

Specification of Letters Patent.

Patented Dec. 12, 1905.

Application filed May 24, 1905. Serial No. 262,055.

To all whom it may concern:

Be it known that I, ALEXIS VERNAZ, mechanician, a citizen of Switzerland, residing at Yverdon, canton of Vaud, Switzerland, have 5 invented new and useful Improvements in Files, of which the following is a specification.

My invention relates to improvements in files, and has for its object the provision of an improved form of tooth especially adapted 10 for files having flat working faces.

To this end my invention consists in a file provided with teeth in the form of segments or arcs the centers of which coincide with the axis of the file and the bases or chords of 15 which are rearwardly disposed with respect to the cutting edges of the teeth.

In the drawings, Figure 1 illustrates a face view of a file provided with teeth embodying the main features of my invention. Fig. 2 is 20 a sectional view on line A B of Fig. 1.

The file herein shown is provided with a main body portion in which the teeth are formed and a reduced end portion provided with a handle. The teeth *a* are shown in the 25 form of arcs or segments extending entirely across the working face of the file, the radii being equal and the centers coincident with the axis of the file. The bases or chords of the arcs are located rearwardly with respect

30 to the cutting edge of the teeth. Thus the comminuted particles or filings will be discharged rearwardly with respect to the direction of the filing stroke, it being well understood that the operating or filing stroke is 35 made in the direction in which the cutting edges of the teeth project. In the embodiment shown the filing stroke would be in the direction indicated by the arrow. By means of this construction a full and effective dis-

40 charge for the comminuted filings is provided, rendering the file substantially self-cleaning. In filing the workman rarely strokes the surface in a plane coincident or parallel with the axis of the file, but usually at an angle 45 thereto. If the teeth of the file are cut in straight lines arranged either at right angles or at other than right angles to the axis of the file, the angular filing movement will result in a greater resistance of one side of the file 50 with the surface operated on than the other

side. In other words, certain portions of the teeth will engage the surface to be filed more actively than others. This results in a tendency of the file to depart sidewise from its course or the direction of the stroke in a manner known in the shop as "chasing." This sidewise movement of the file requires that the operator overcome not only the usual resistance of the filing operation, but also the tendency of the file to "chase." Furthermore, in a file that has the foregoing defect the parts of the teeth which first and most actively engage the material are the first to wear down, thereby rendering the file inefficient and sometimes useless when the teeth are 65 only partially worn off. With teeth formed according to the present invention there is always a cutting-surface presented at right angles to any probable angularity of stroke. Thus the normal tendency to chase is prevented. Furthermore, the filing-surface is uniformly active in engaging the material. Therefore no one portion of the file can be prematurely worn off. This, added to the self-cleaning feature, constitutes a construction 70 combining features of special advantage.

While I have herein shown a file wherein the radii of the teeth are equal, it will be understood that I do not wish to be limited to this precise feature of construction, as the advantages of the invention could be realized if the radii were unequal so long as the centers are coincident with the axis of the file and the bases of the arcs are rearwardly located with respect to the cutting edge of the teeth. 85

Having now described my invention, I claim as new and wish to secure by Letters Patent—

1. A file provided with teeth cut in the form of arcs having equal radii the centers of which coincide with the axis of the file. 90

2. A file provided with teeth cut in the form of arcs having their centers coincident with the axis of the file.

3. A file provided with teeth cut in the form of arcs having their centers coincident with the axis of the file and the bases of the arcs located rearwardly with respect to the cutting edges of the teeth. 95

4. A file provided with teeth cut in the 100

form of arcs having their bases located rearwardly with respect to the cutting edge of the teeth.

5. A file provided with teeth cut in the form of arcs having equal radii, the centers of which coincide with the axis of the file, the bases of said arcs being rearwardly disposed with respect to the cutting edge of the teeth.

In testimony whereof I have signed my name to this specification in the presence of two subscribing witnesses.

ALEXIS VERNAZ.
